HINGE

Albert F. Lickteig, Grand Rapids, Mich., assignor
to Grand Rapids Brass Company, Grand
Rapids, Mich., a corporation of Michigan

Application June 23, 1937, Serial No. 149,847

3 Claims. (Cl. 16—184)

The present invention relates to hinges and more particularly to refrigerator door hinges.

The primary objects of the instant invention are to provide a hinge of the general character above indicated having a stop for governing the normal limit of the opening movement of a door; to provide such a hinge whose stop forms a brake for doors carelessly swung by force beyond their normal limit of opening movement; to provide such a hinge whose stop is movable under tension when the door is carelessly swung by force past its normal limit of opening movement; to provide such a hinge whose stop is designed to minimize chipping or marring of the door surface and the surface of the body on which it is hung by the contact of the surface of the door against the surface of said body; and to provide such a hinge which is attractive in appearance, which may be readily installed, which is efficient in use and which is reasonably economical in manufacture.

An illustrative embodiment of the invention is shown in the accompanying drawing, wherein:

Figure 1 is a longitudinal vertical central sectional view of the hinge and on line 1—1 of Figure 3;

Figure 2 is a sectional view thereof on line 2—2 of Figure 1;

Figure 3 is a sectional view on line 3—3 of Figure 1 and showing the door swung to its closed position from its open positions shown in Figures 4 and 5;

Figure 4 is a sectional view similar to Figure 3 but showing the door swung to its normal limit of opening movement; and

Figure 5 is a sectional view similar to the view shown in Figure 4 but showing the door carelessly forced beyond its normal limit of opening movement.

Referring then to the drawing wherein like parts of the structure are designated by the same numerals in the several views, the hinge as there shown comprises a U-shaped leaf, generally designated 10, whose middle portion is adapted to be secured to a door 11 of a refrigerator or the like as by screws 12 and a second U-shaped leaf, generally designated 13, whose middle portion is adapted to be secured adjacent a door jamb 14 of a refrigerator cabinet or the like as by screws 15.

The projecting end portions or ears 16 of the door leaf 10 are disposed between and interjacent the projecting portions or ears 17 of the jamb leaf 13 and pintles 18 pivotally secure the ears of the leaves together. The head of each

pintle is here shown as provided with a hexagonal shank 19 seated within a hexagonal well of each ear 17 to prevent rotation of the pintle relative to the leaf 13 and each pintle is further provided with a rounded shank portion 20 disposed through a bore 21 of each ear 16 permitting a swinging movement of the door 11 relative to its jamb 14.

A leaf spring 22 is seated at its opposite ends in wells 23 in the inside surfaces of each ear 16 and its middle portion is held against lateral movement by lugs 24 struck up on opposite sides of the leaf 10 and substantially medially of its length.

Each pintle is further provided with a cammed portion 25 adjacent its inner end and a swinging movement of the door 11 from its closed position shown in Figure 3 to its normal limit of opening movement shown in Figure 4 causes the leaf spring 22 to engage the cammed portion 25 of each pintle 18.

Forced movement of the door beyond its normal limit of opening movement shown in Figure 4 to its position shown in Figure 5 compresses the leaf spring 22 as shown in Figure 5 which serves as a brake for a movement of the door beyond its normal limit of movement and minimizes chipping or marring of the door surface and the surface of the cabinet on which the door is hung.

A housing 26 for the door leaf 10 may be provided if desired and the hinge otherwise dressed up. It will thus be seen that the hinge herein shown and described is especially well adapted for use with refrigerator doors and that it is attractive in appearance, may be readily and conveniently installed, is efficient in its intended use and is reasonably economical in manufacture.

While but one specific embodiment of the invention has been herein shown and described, it will be understood that certain details of the construction shown may be altered or omitted without departing from the spirit of the invention as the same is defined by the following claims.

I claim:

1. A hinge having a U-shaped leaf whose middle portion is adapted for installation adjacent a door jamb and a U-shaped leaf whose middle portion is adapted for installation on a door and whose projecting end portions are disposed between the projecting end portions of said jamb leaf, pintles pivotally securing the adjacent projecting end portions of said leaves together and provided with cammed portions, and a spring 55

carried by one of said leaves normally spaced from said pintles and their cammed portions but adapted to be engaged by the cammed portion of each pintle at a predetermined phase in the 5 swinging movement in one direction of one leaf relative to the other leaf and serving as a brake for a forced movement of one leaf beyond the normal limit of its movement in said direction.

2. In a hinge, a U-shaped leaf whose middle portion is adapted for installation adjacent a 10 door jamb, pintles non-rotatably disposed in the projecting end portions of said jamb leaf and having rounded shank portions and cammed portions, a second U-shaped leaf whose middle portion is adapted for installation on a door and whose projecting end portions are pivotally 15 mounted on the rounded shank portions of said pintles, and a spring carried by the door leaf having end portions normally spaced from said 20 pintles and their cammed portions but adapted to be engaged by the cammed portions of said pintles at a predetermined phase in the opening swinging movement of the door leaf relative to the jamb leaf and serving as a brake for a forced

movement of said door leaf beyond the normal limit of said movement.

3. In a hinge, a U-shaped leaf whose middle portion is adapted for installation adjacent a door jamb; pintles non-rotatably disposed in the 5 projecting end portions of said jamb leaf and having rounded shank portions and cammed portions, a second U-shaped leaf whose middle portion is adapted for installation on a door and whose projecting end portions are pivotally 10 mounted on the rounded shank portions of said pintles and are provided with spring retaining wells therein, and a spring mounted on the door leaf and having springable end portions yieldingly 15 retained in said wells and normally spaced from said pintles and their cammed portions but adapted to be compressed by the cammed portions of said pintles at a predetermined phase in the opening swinging movement of the door leaf relative to the jamb leaf and serving as a brake 20 for a forced movement of said door leaf beyond the normal limit of said movement.

ALBERT F. LICKTEIG.
